CLAIM

The ornamental design for a chicken leg pet treat, as shown and described.

DESCRIPTION

FIG. 1 is front, top and left side perspective view of a first embodiment of a chicken leg pet treat according to the new design;

FIG. 2 is a back, bottom and left side perspective view of the embodiment of FIG. 1;

FIG. 3 is a front view of the embodiment of FIG. 1;
FIG. 4 is a back view of the embodiment of FIG. 1;
FIG. 5 is a top plan view of the embodiment of FIG. 1;
FIG. 6 is a bottom plan view of the embodiment of FIG. 1;
FIG. 7 is a left side elevation view of the embodiment of FIG. 1;

FIG. 8 is a right side elevation view of the embodiment of FIG. 1;

FIG. 9 is front, top and left side perspective view of a second embodiment of a chicken leg pet treat according to the new design;

FIG. 10 is a back, bottom and left side perspective view of the embodiment of FIG. 9;

FIG. 11 is a front view of the embodiment of FIG. 9;
FIG. 12 is a back view of the embodiment of FIG. 9;
FIG. 13 is a top plan view of the embodiment of FIG. 9;
FIG. 14 is a bottom plan view of the embodiment of FIG. 9;
FIG. 15 is a left side elevation view of the embodiment of FIG. 9; and,

FIG. 16 is a right side elevation view of the embodiment of FIG. 9.
